UNITED STATES PATENT OFFICE.

WALTER L. HENDRICKS, OF AURORA, ILLINOIS.

HARVESTING MACHINE.

1,424,746.

Specification of Letters Patent. Patented Aug. 1, 1922.

Application filed January 25, 1918. Serial No. 213,758.

To all whom it may concern:

Be it known that I, WALTER L. HENDRICKS, a citizen of the United States, and resident of Aurora, county of Kane, and State of Illinois, have invented certain new and useful Improvements in Harvesting Machines, of which the following is a specification, and which are illustrated in the accompanying drawings, forming a part thereof.

10 The invention relates to harvesting machines and particularly to those which are employed for reaping grain and tying it into bundles and are of the general type illustrated in Patent No. 1,177,104 issued to me 15 March 28, 1916. The object of the invention is to provide an improved machine of this type, the improvements being especially concerned with the mechanism provided for steering and the means employed for supporting and vertically adjusting the operative parts. One embodiment of the invention 20 is illustrated in the accompanying drawings; wherein—

Fig. 1 is a general plan view of the machine,

Fig. 2 is a side view of the same, some of the parts being broken away, and other parts shown in section,

Fig. 3 is a detail perspective view of an 30 equalizing device,

Fig. 4 is a detail perspective view showing a portion of the pole,

Fig. 5 is a sectional view taken on the line 5—5 of Fig. 1, and

Fig. 6 is a perspective view of one of the rear wheels.

As in the construction shown in my said former patent, power for driving the operative parts of the machine is derived from 40 a pair of front carrying wheels 10, 10, and the axle, as 28, upon which these wheels are mounted extends beneath and supports an inclined stub tongue 22. In this instance, however, the front carrying wheels 10, 10, 45 are preferably rigid and the turning of the machine is accommodated by the swinging of the rear wheels 11 and 12, two of which are shown. For this purpose, both of the rear wheels 11 and 12 are mounted upon 50 vertical spindles, as 51 and 51^a. One of the rear wheels, as 12, is located in rear of the platform, generally designated 70, and no grain wheel is employed. All of the supporting wheels are thus arranged within the 55 path of movement of the outer end of the sickle bar represented at 16.

The main frame of the machine is generally designated 13. At its front end, this frame is pivotally connected with the rear end of the stub tongue 22, as at 15, (Fig. 60 2), while brackets 52 and 81 are provided at the rear of this frame for rotatably receiving the vertical spindles 51 and 51^a, of the rear wheels 11 and 12. The operative parts of the machine, including the sickle bar 16, 65 and the bundle tying mechanism 75 are associated upon the main frame 13. The particular form and arrangement of these parts constitute no part of the present invention and they are not illustrated in detail except that owing to the omission of the grain wheel special provision is made for supporting the platform 70 at its outer end and this feature is fully illustrated.

The chief reason for omitting the grain 75 wheel is that, as heretofore employed it was customarily located beyond the end of the sickle bar and therefore bent down and crushed a portion of the standing grain which would not therefore be cut by the 80 machine on the next swath. Another reason for omitting the grain wheel in the present construction is the difficulty which would be involved in turning the machine with fixed grain and bull wheels. Furthermore, 85 the omission of the grain wheel provides an arrangement in which the axis of tilting for vertical adjustment is parallel with the sickle bar, and is situated in the rear of the platform.

Owing to the improved arrangement of the carrying wheels, the platform 70 is constructed to prevent sagging at the outer end of the sickle bar 16. As shown, the platform frame comprises the main rear and 95 front frame members 82, 83, (Fig. 5) and a supplemental rear frame member 71. These three frame members are rigidly connected at the outer end of the platform by the end frame piece 84 and a diagonal brace 86. 100 100 connects the rear and front frame members 82, 83, intermediate their ends. The three frame members 71, 82, and 83 are also connected by an intermediate frame member 85 which extends under the platform and is 105 turned upwardly at its rear end to provide a post 81^a against which the bracket 81 is secured.

The supplemental frame member 71 is conveniently made tubular and this frame 110 member is preferably turned upwardly at its outer end, forming an upright post 72^a.

at the outer rear corner of the platform. This post is provided for connection with the end of a stay 73 which extends from and is secured to the outer front corner of the platform. As shown, a threaded tensioning bolt 73^a is employed for connecting the stay 73 with the upper end of the post. As this arrangement requires that the supplemental frame member 71 must be firmly held against twisting, the inner end portions 71^a (Fig. 2) of this frame member is preferably turned forwardly and supported in a stirrup 71^b. For convenience of illustration the platform conveyor 70^a is shown as being of usual form.

As in my earlier form of construction the height of the sickle bar above the ground may be adjusted by varying the angle between the stub tongue and the main frame. In the present construction this relative movement of the main frame and stub tongue is preferably accomplished by a simple lever and toggle device.

As shown, a lever 17 is pivotally mounted on the frame 18 at the point 18. The forward end 19 of this lever is connected at 20 to a yoke 21 in turn pivoted to the stub tongue 22, so that, if the lever 17 is depressed the point 15 is also depressed, and vice versa.

As the weight of the machine tends to force the point 15 downward a stout spring 23 is connected at one end to the stub tongue 22 by means of the bracket 24 and at its other end at 25 to the lower part of the yoke 21 so that its tension acts in opposition to the forces of gravity. It will also be noted that when the tension of the spring 23 is weakest the forward part 19 of the lever 17, and the yoke 21, forming a toggle joint, provide their maximum leverage.

The raising and lowering of the machine produces corresponding changes in the angle of the stub tongue and thereby varies the height of the pivotal connection between the latter and the pole 34. It is important that this height should not change to any great extent as otherwise the efficiency of the machine will be impaired. Thus when power is obtained from the carrying wheels it has been found that the pressure on the driving or "bull" wheels, produced by the dead weight of the machine, can be supplemented to advantage by connecting the harvester to the draft means, whether horse or tractor, in such a way that the pull on the pole tends not only to move the harvester forward but also to press the driving wheels against the ground. It follows that if the driving wheels are arranged at the front of the machine and the draft pole is connected to the harvester at a point above the axle, the effective downward pressure on the driving wheels is substantially increased.

When horses are used it is also important

that the whiffle-tree 36 mounted on the draft pole should be maintained at a suitable elevation with respect to the height of the team, regardless of vertical adjustment of the operative parts of the machine. In order to adjust the position of the pole relatively to the stub tongue so as to keep the whiffle-tree substantially the same height above the ground, irrespective of the height of the machine, the stub tongue is provided with an extension 30 adjustably connected thereto. On each side of this extension 30 are bolted plates 31 having rearward extensions 32 of segmental form. Adjacent the outer edge of these segments are arranged a series of apertures 33 adapted to register with a hole in the end of the stub tongue 22. By means of a pin or bolt passed through one or the other of the apertures 33 the stub tongue 22 and the plates 31 may be locked in any desired angular position. In this way the position of the rear end of the pole and the whiffle-tree and the stub tongue extension 30 relatively to the front part of the machine may be varied as the height of the machine above the ground is varied. The pole is free to swing relatively to this extension by means of the yoke 35 between the arms of which the pole is pivotally held.

The power for driving the machine is taken from the front wheels and preferably therefore in order to facilitate the transference of power the front wheels are mounted directly on a stationary axle and the machine is steered by the rear wheels.

For transmitting power from the front wheels to the reaping mechanism a sprocket wheel 76 is mounted on the shaft 28 which carries the wheel 10. From this sprocket wheel a chain 77 leads to a sprocket 78 under the main part of the machine. In view of the fact that as the machine is raised and lowered the sprocket wheels 76 and 78 recede from and approach each other, a tension wheel 79 is preferably provided on the end of a pivotally mounted arm 80 which is held in contact with the chain 77 by means of a spring 80.

While the pole is arranged to swing laterally for steering, instead of swinging the front wheels, one of the rear wheels is turned thereby. It is not essential to swing both rear wheels positively and the second rear wheel may be arranged to have a castor-like action. For the purpose of allowing the pole to swing in a horizontal arc relatively to the stub tongue a yoke 37 is attached to the rear of the yoke 35 engaging the stub tongue extension 30 on its upper and under surfaces. A bolt 38 pivotally connects the yoke 37 to the extension 30. Lateral movements of the pole and yoke 37 are transmitted to the rear wheel 11 by means of a system of links and levers. On the yoke 37

is arranged an angle piece 63 carrying a bracket 62 to which the forward end of a rod 61 is connected. The rear end of the rod 61 is attached to one end of a rocker 60 on the lower end of the stub tongue 22. To the other end 59 of the rocker 60 is connected the forward end of a rod 54 leading to the rear wheel 11. The wheel 11 is mounted between the arms of a fork 50 having a verticle shaft 51 attached to its upper end and journaled in the part 52 of the frame. Extending laterally from the fork 50 is a bracket or angle piece 53 to which is pivotally and yieldingly connected a rod 54. This rod 54 is resiliently connected to the angle piece 53 by means of a link 55 formed with a central aperture for springs 56 mounted on either side of a collar 57 on the rod 54 which slides through the end walls of the apertured portion of the link.

By means of the rods 54 and 61, rocker 60 and the other parts above referred to, if the pole swings to the left, for example, the yoke 37 will pivot on the stub tongue extension 30 thereby drawing the rod 61 forward and pushing the rod 54 rearwardly by means of the rocker 60. The backward movement of the rod 54 turns the forward part of the rear wheel 11 to the right thereby turning the whole machine toward the left, as required.

When the machine is raised and lowered the distance between the rear wheel and the stub tongue extension changes so that to avoid turning the rear wheel to one side when the machine is raised or lowered, provision is made for adjusting the position of the rocker 60 with such movements. The pivot 64 of the rocker is, therefore, mounted on a slide 65 adapted to be moved to and fro between guides 66 by means of a link 67 connected at one end to lugs 68 on the slide and at the other end to the frame at the point 69. The point 69 is so located that when the machine is lowered the link 67 moves the slide 65 forward sufficiently to compensate for the shortening of the distance between the rear wheel 11 and the stub tongue extension 30.

In some cases, for instance when the machine is being driven along the side of a hill, it may be desirable to prevent the pole swinging and thereby turning the rear wheels since such turning movement tends to allow the rear end of the machine to swerve down the hill. This may be accomplished by preventing the pole swinging laterally relatively to the stub tongue extension 30 by means of a locking rod or bolt 42. This rod is slidably supported by two angle pieces 40 and 41 mounted on the upper surface of the stub tongue extension 30. A similar angle piece 39 is arranged on the rear part of the yoke 37 having an

aperture 43 adapted to receive the end of the rod 42 and thereby prevent rotation of the yoke 37 about the bolt 38.

On this rod 42 is a shoulder 44 for engaging a spring 45, the other end of the spring bearing against the angle piece 41 so that the spring tends to hold the rod in engagement with the aperture 43. Normally the rod 42 is held retracted against the force of this spring by means of a link 46 connected to a rocker 48. The lower end of this rocker is engaged in its retracted position by means of a spring-held pawl 47 adapted to be operated by the foot. Sufficient play is allowed by the spring 45 to compensate for movements of the rods 42 and 46 produced by raising and lowering the machine.

If the pole is prevented from swinging horizontally as the result of the engagement of the locking rod or bolt 42 with the angle piece 39 it is desirable, if not essential, to disconnect the rear wheel steering mechanism above described so as to allow the wheel 11 to act as a caster. Preferably, the steering mechanism is disconnected at the wheel 11 in order to give the fullest freedom to the latter.

In the construction shown the other rear wheel 12 is arranged to act as a caster at all times. As the harvester is constructed so that the pull on the machine produces a downward pressure on the driving or "bull" wheels it is desirable to make these wheels wider than has hitherto been customary. For this purpose additional wheels or lateral extensions 72 of the rims of the wheels 10 may be secured thereto. These extensions are particularly useful in rice fields where the ground is extremely soft and marshy.

I claim as my invention:

1. In a harvesting machine, in combination, a frame, front and rear carrying wheels for the frame, said frame comprising two sections pivotally connected at a point between said wheels, means for changing the vertical angular relation between said sections, a pole, an intermediate member between said pole and the forward section and connected to both and means for changing the vertical angular relation of the intermediate member relatively to the section to which it is connected.

2. In a harvesting machine, in combination, a frame, a platform, carrying wheels for the frame, said frame comprising a cross beam at the rear of the platform, a vertical extension at the end of said beam and a brace extending from the upper part of said extension to the forward portion of the frame in a vertical plane substantially parallel with the end of the platform.

3. In a harvesting machine, in combination, a frame, comprising front and rear sections pivoted together, front and rear carrying wheels for said sections, a pole connected

to said front section adapted to move in a horizontal arc relatively thereto, and a rocker on said front section adapted to be turned by movements of said pole, one of said rear wheels being operatively connected to said rocker by which it is steered.

4. In a harvesting machine, in combination, a frame comprising front and rear sections pivoted together, front and rear carrying wheels for said sections, a pole connected to said front section to move in a horizontal arc relatively thereto, a rocker on said front section turned by movements of said pole, one of said rear wheels being operatively connected to said rocker by which it is steered, and means for changing the position of said rocker relative to the front section with changes in the angular relation between the sections.

5. In a harvesting machine, in combination, a frame comprising front and rear sections pivoted together, front and rear carrying wheels for said sections, the point of connection of said sections being intermediate said front and rear wheels, a spring adapted to exert an upward pressure on said point of connection and manually operated means for varying the angular relation of said sections to each other.

6. In combination, a harvester frame, reaping and binding mechanism mounted in the frame including a sickle bar extending along the front edge of the frame from one side thereof but not reaching to the other side of the frame, a pair of relatively widely separated carrying wheels located upon a common transverse line at the rear of the frame and constituting a support therefor upon which the frame may be tilted to change the elevation of the said sickle bar, both of the said carrying wheels being located laterally within the outer end of the sickle bar, a truck located in front of the frame laterally beyond the inner end of the sickle bar, a vertically adjustable draft connection between the front edge of the frame and the truck and power transmitting mechanism extending from the truck to the said reaping and binding mechanism, said rear carrying wheels and said truck constituting the only supports for the frame.

7. In combination, a harvester frame, caster wheel supporting means at the rear of the frame upon which the frame may be tilted to change the elevation of its forward edge, a draft truck located in front of the frame and a vertically adjustable but horizontally rigid draft connection between the draft truck and the front of the frame, said draft truck and said caster wheel supporting means constituting the only supports for the frame.

8. A harvesting machine, a substantially level main frame and an upwardly inclined supplemental frame arranged in advance

thereof and pivotally attached thereto for motion about a horizontal axis, carrying wheels at the rear of the main frame, carrying and driving wheels under the central portion of the supplemental frame, means for controlling movement of the supplemental frame about said horizontal axis and a draft tongue attached to the upper end of the supplemental frame whereby draft will increase the pressure of the last named wheels upon the ground.

9. In combination, a harvester frame, carrying wheels having vertical pivotal connections with the frame adjacent the rear end of the same to permit swinging of the wheels during turning of the frame, the said wheels constituting a support for the frame upon which it may be tilted to change the elevation of the frame at its forward edge, a draft truck in front of the frame and a vertically adjustable but horizontally rigid draft connection between the draft truck and the front of the frame, the said draft truck and said rear carrying wheels constituting the only supports for the frame.

10. In combination, a harvester frame, reaping and binding mechanism mounted in the frame including a sickle bar extending along the front edge of the frame from one side thereof but not reaching to the other side of the frame, a caster wheel supporting means at the rear of the frame upon which the frame may be tilted to change the elevation of the said sickle bar, the said caster wheel supporting means being located laterally within the outer end of the sickle bar, a truck located in front of the frame laterally beyond the inner end of the sickle bar, a vertically adjustable but horizontally rigid draft connection between the front of the frame and the truck, and power transmitting mechanism extending from the truck to the said reaping and binding mechanism, the said caster wheel supporting means and the said truck constituting the only supports for the harvester frame.

11. In combination, a harvester frame, a carrying wheel constituting a support upon which the frame may be tilted, a draft truck located in front of the frame, a vertically swinging but horizontally rigid draft member pivotally connected to the front of the frame and to the draft truck, manually operable means for swinging the said draft member upon its said pivotal connection with the draft truck as a fulcrum to accomplish the said tilting of the harvester frame, and a lifting spring reacting between the harvester frame and the said draft member.

12. In combination, a harvester frame comprising a grain platform at one side of the frame, a sickle bar extending along the front edge of the grain platform, a draft truck supporting the front edge of the frame at the side remote from the grain platform,

- carrying wheels supporting the rear edge of the frame, the outer corner of the grain platform having no direct support upon the ground, a torsion member extending transversely of the frame adjacent its rear edge, means anchoring the end of the torsion member remote from the outer side edge of the grain platform and supporting means acting between the torsion member and the forward portion of the grain platform. 25
13. In combination, a harvester frame comprising, a grain platform at one side of the frame, a sickle bar extending along the front edge of the grain platform, a draft truck supporting the front edge of the frame at the side remote from the grain platform, carrying wheels supporting the rear edge of the frame, the outer front corner of the grain platform having no direct support 30
- upon the ground, a torsion member extending transversely of the frame adjacent its rear edge, means anchoring the end of the torsion member remote from the outer side edge of the grain platform and adjustable 35
- supporting means acting between the torsion member and the forward portion of the grain platform. 40
14. In a harvesting machine, in combination, a wheeled power section and a wheeled operating section hingedly connected at the forward end of the operating section and the rearward end of the power section for vertical flexure only, all of the supporting wheels of the operating section being substantially in transverse alignment and each 45 of said wheels having pivotal movement upon a vertical axis. 45
15. In a harvesting machine, in combination, a wheeled power section and a wheeled operating section hingedly connected at the forward end of the operating section and the rearward end of the power section for vertical flexure, only, all of the supporting wheels of the operating section being at the rear margin of said section and each of said 50 wheels having pivotal movement upon a vertical axis. 50

WALTER L. HENDRICKS.
